(57) **CLAIM**

The ornamental design for a phone stand with speaker and clock, as shown and described.

DESCRIPTION

FIG. 1 is a front, right, and top perspective view of a phone stand with speaker and clock showing my new design; FIG. 2 is a front, right, and bottom perspective view thereof; FIG. 3 is a rear, left, and bottom perspective view thereof; FIG. 4 is a front elevation view thereof; FIG. 5 is a rear elevation view thereof; FIG. 6 is a left side elevation view thereof; FIG. 7 is a right side elevation view thereof; FIG. 8 is a top plan view thereof; FIG. 9 is a bottom plan view thereof; FIG. 10 is an enlarged view of portion 10 shown in FIG. 1; FIG. 11 is a front, right, and top perspective view thereof, where the phone stand with speaker and clock is in a folded state; FIG. 12 is a front, right, and top perspective view thereof, where the phone stand is rotated to another position, and the kickstand for supporting a mobile phone is in a folded state; and, FIG. 13 is an exploded front, right, and top perspective view thereof, where the clock is separated from the main body. The dash-dash broken lines in the drawings depict portions of the phone stand with speaker and clock that form no part of the claimed design. The dot-dash broken lines in FIGS. 1 and 10 represent the boundaries of the enlarged portion and form no part of the claimed design.

1 Claim, 13 Drawing Sheets
